UNITED STATES PATENT OFFICE.

WILLIAM A. GEIGER, OF CHICAGO, ILLINOIS, ASSIGNOR TO W. H. MINER, INC., OF CHICAGO, ILLINOIS, A CORPORATION OF DELAWARE.

DRAFT-RIGGING-KEY RETAINER.

Application filed October 12, 1925. Serial No. 61,929.

This invention relates to improvements in draft rigging key retainers.

One object of the invention is to provide a readily detachable, reliable retaining means for keys of railway draft riggings, of simple design, which may be economically manufactured and may be employed in connection with railway draft riggings now commonly used without in any manner modifying the construction of the draft rigging itself.

A more specific object of the invention is to provide a retaining bracket in the form of a Z-bar adapted for attachment to the vertical web of one of the draft sills of a railway draft rigging adjacent the key receiving opening thereof, and having a section thereof overlapping the corresponding end of the key to prevent accidental removal of the key outwardly of the sill.

A still further object of the invention is to provide a retaining means of the character described which may be attached to one or both of the draft sills of a railway underframe, whereby either a headed key of the usual type or plain unheaded key in the form of a flat bar may be employed.

Other objects of my invention will more fully appear from the description and claims hereinafter following.

In the drawing forming a part of this specification, Figure 1 is a side elevational view, partly broken away and partly in section, of a portion of a railway draft rigging showing my improvements in connection therewith. And Figure 2 is a vertical transverse sectional view corresponding substantially to the line 2—2 of Figure 1.

In said drawings 10—10 indicate the usual channel-shaped center or draft sills of a railway car underframe having front and rear stop lugs secured to the inner sides thereof. The front stop lugs only are shown in the drawing and are designated by 11—11. The inner end of the draw bar is indicated by 12, to which is operatively connected a hooded yoke 13 of usual form. The draw bar and the yoke are provided, respectively, with aligned openings 14 and 15 adapted to receive a key 16. The key illustrated in the drawings is of the headless type, being in the form of a substantially flat bar. The opposite ends of the bar or key 16 work in the usual aligned key-receiving slots 17—17, provided in the draft sills.

The draft lugs are also provided with key receiving openings 18 aligned with the openings 17 of the sills. As most clearly shown in Figure 2, the key 16 is of such a length as to extend outwardly beyond the planes of the draft sills.

A pair of retaining members 19—19 are associated with each key 16 of the draft rigging, each retaining member being in the form of a Z-bar having vertically disposed sections 20 and 21 and a horizontally disposed intermediate section 22. Each Z-bar 19 is detachably secured to the web of the corresponding draft sill 10 by any suitable means, preferably by retaining bolts 23, accommodated in the usual receiving openings of the draft sills and stop lugs. As most clearly shown in Figure 2, the Z-bars are disposed below the key-receiving openings 17 of the draft sills and each bar has the horizontal section 22 thereof preferably disposed in alignment with the lower edge of the corresponding key receiving opening, thereby forming a supporting ledge for the adjacent end of the key. The section 21 of the Z-bar 19, which is vertically disposed, cooperates with the outer end of the key to prevent accidental removal thereof in a direction outwardly of the sill. A certain amount of clearance is provided between the ends of the key and the vertical sections 21 of the Z-bars 19, thereby permitting play between the parts and reducing wear on the retaining members to a minimum. As most clearly shown in Figure 1, the sections 21 are of such a width longitudinally of the sills that they will at all times overlap the corresponding ends of the key during the extent of movement of the same in the slots 17 of the sills.

It will be evident that the key may be easily removed or replaced by detaching either one or both of the retaining members 19 associated therewith. Inasmuch as the key may be removed in either direction outwardly of the sills, it will be evident that detachment of the same is greatly facilitated in case the key becomes jammed or wedged in one direction or removal thereof is prevented by an obstruction.

Although only one key and set of cooperating retaining members is shown in the drawings, it will be evident that my invention may be applied to any or all of the keys of a railway draft rigging employing

a plurality of keys, in which case a retaining means of the type shown is employed in connection with each key.

It will also be evident that my improved retaining means may be employed in connection with the usual key of the headed type, in which instance the retaining means is applied to one sill only and cooperates with the headed end of the key.

10 Although I have herein shown and described what I now consider the preferred manner of carrying out my invention, the same is merely illustrative and I contemplate all changes and modifications that 15 come within the scope of the claims appended hereto.

I claim:

1. In a railway draft rigging, the combination with draft sills having aligned key receiving openings and a connecting key working in said openings and having the ends thereof projecting through the sills and beyond the outer sides of the same; of means for limiting endwise movement of said key 25 to retain it in assembled relation with the draft rigging, said means including a detachable, rigid bracket fixed to each sill adjacent the key receiving opening thereof, each of said brackets having one end section thereof secured to a draft sill and having the other free end section thereof overlapping the corresponding end of the key.

2. In a railway draft rigging, the combination with draft sills having vertically disposed web sections provided with aligned key receiving openings and a key having the opposite ends thereof working in said openings; of a one-piece rigid retaining element detachably secured to the vertical web of one

of the sills below the key receiving opening, 40 said bracket having an upwardly extending free end section overlapping a portion of the corresponding end of the key in any longitudinal position of the latter while within said slot to prevent accidental removal of 45 the key outwardly of said sill.

3. In a retaining means for a connecting key of a draft rigging, wherein the key extends transversely of the sills and has one end thereof projecting outwardly beyond the 50 plane of one sill through the slot therein, the combination with a retaining element secured to the outer side of said sill, said retaining element having a horizontal section supporting the corresponding end section of 55 the key and a vertically free end section overlapping a portion of the corresponding end of said key to prevent accidental removal of the key from the corresponding side of the draft sills.

4. In a railway draft rigging, the combination with spaced draft sills having aligned key receiving openings and a connecting draft rigging key working in said openings, and having the opposite ends 65 thereof extending through said openings beyond the outer sides of the sills; of a retaining bracket secured to one of said draft sills, said bracket being in the form of a Z-bar having one of the flanges thereof disposed outwardly of the corresponding end of the key and overlapping said end to prevent accidental removal of the key outwardly of said sill.

In witness that I claim the foregoing I 75 have hereunto subscribed my name this 8th day of October 1925.

WILLIAM A. GEIGER.
